UNITED STATES PATENT OFFICE.

WILLIAM H. HART, JR., OF PHILADELPHIA, PENNSYLVANIA.

DESIGN FOR A BICYCLE-SUPPORT.

SPECIFICATION forming part of Design No. 31,480, dated August 29, 1899.

Application filed August 3, 1899. Serial No. 726,053. Term of patent 7 years.

To all whom it may concern:

Be it known that I, WILLIAM H. HART, Jr., a citizen of the United States, residing in the city and county of Philadelphia, State of Pennsylvania, have invented and produced a new and original Design for a Bicycle-Support, of which the following is a specification, reference being had to the accompanying drawings, forming part thereof.

10 The leading feature of my design for a bicycle-support is a leg of flaring form and an inturned limb on the upper end thereof.

Figure 1 represents a perspective view of a bicycle-support embodying my design. Fig. 15 2 represents a vertical section on line $x-x$, Fig. 1.

In the drawings, A designates legs, and B the base thereof. On the upper ends of the legs are limbs C, which project therefrom inwardly or toward each other. The legs flare 20 from their upper portions D to the base B.

Having thus described my invention, what I claim as new, and desire to secure by Letters Patent, is—

25 The design for a bicycle-support substantially as shown and described.

WILLIAM H. HART, JR.
